UNITED STATES PATENT OFFICE.

SAMUEL C. KINDIG, OF BALTIMORE, MARYLAND, ASSIGNOR OF ONE-HALF TO WILLIAM C. LUDWIG, OF BALTIMORE, MARYLAND.

BROOM-HOLDER.

1,329,186.

Specification of Letters Patent. Patented Jan. 27, 1920.

Application filed May 28, 1919. Serial No. 300,354.

To all whom it may concern:

Be it known that I, SAMUEL C. KINDIG, a citizen of the United States, residing at Baltimore, in the State of Maryland, have 5 invented certain new and useful Improvements in Broom-Holders, of which the following is a specification.

This invention relates to improvements in broom holders, and has for its object to 10 provide a simple, cheap and efficient device which can be secured to the side of the wall, door frame or other suitable place and in which the broom is securely and conveniently held, and from which it can be readily 15 removed when desired.

The invention consists of the novel construction and arrangement of the parts and combination of parts hereinafter more fully set forth in the following specification and 20 pointed out in detail in the appended claim.

In the accompanying drawing.—

Figure 1 is a front elevation of my invention showing the position of the broom in dotted lines.

25 Fig. 2 is a top plan view of Fig. 1.

Fig. 3 is a side view of Fig. 1.

Referring to the accompanying drawings forming part of this specification and in which like reference numerals designate 30 like parts throughout the several views thereof, 1 designates the broom rest which is formed by bending the ends 2 around at the front leaving an opening therebetween through which the broom handle passes

when the broom is being placed in position 35 in the holder. The wire is then bent down at 3 and twisted to strengthen it and then bent laterally forming the arms 4 through which the screws 5 or other suitable fastening devices are passed to hold the device in 40 position. The wire is then bent downwardly at 6 and then bent to form the resilient clamp 7. The outer ends 8 of which latter are bent over and back against said clamp to form a guide for the broom 45 handle as it is forced between the clamp 7.

To place the broom in position the handle is forced between the clamp 7 and also passes between the ends 2 of the rest and then lowered down into said rest 1, the 50 clamp 7 holding the broom securely in position.

Having thus described my invention, what I claim is:—

A broom holder formed with a rest at 55 its upper end adapted to receive the straw end of the broom and having its ends apart to form an opening for the broom handle, a piece projecting downwardly from said rest and having two laterally projecting arms 60 each having an opening in its outer end, and a clamp at the lower end of said downwardly projecting piece and having its extremities apart and extending around to form a guide for the broom handle. 65

In testimony whereof I affix my signature.

SAMUEL C. KINDIG.
